United States Patent [19]

Luu

US00D324029S

[11] Patent Number: Des. 324,029

[45] Date of Patent: ** Feb. 18, 1992

[54] MULTIPLE ELECTRICAL OUTLET ADAPTER

[75] Inventor: Daniel H. V. Luu, Carmel, Ind.

[73] Assignee: Pacomex Industries, Inc., Indianapolis, Ind.

[**] Term: 14 Years

[21] Appl. No.: 327,571

[22] Filed: Mar. 23, 1989

[52] U.S. Cl. D13/139

[58] Field of Search D13/137, 139, 141, 143, D13/184; D8/350, 352, 353; D10/106, 116, 200/333; 340/635, 638; 220/3.3, 3.8, 241, 242, 337, 339; 174/66, 67, 48; 439/105, 296, 346, 365, 650-653

[57] CLAIM

The ornamental design for a multiple electrical outlet adapter, as shown and described.

DESCRIPTION

FIG. 1 is a front elevational view of a multiple electrical outlet adapter showing my new design;

FIG. 2 is a left side elevational view thereof, the right side elevational view being a mirror image.

FIG. 3 is a top plan view thereof;

FIG. 4 is a bottom plan view thereof;

FIG. 5 is a back elevational view thereof;

FIG. 6 is a left side elevational view of a multiple electrical outlet adapter showing a second embodiment of my new design, the right side elevational view being a mirror image;

FIG. 7 is a bottom plan view thereof, the top plan, front elevational and back elevational views being the same as the first embodiment;

FIG. 8 is a left side elevational view of a multiple electrical outlet adapter showing a third embodiment of my new design, the right side elevational view being a mirror image;

FIG. 9 is a bottom plan view thereof, the top plan, front elevational and back elevational views being the same as the first embodiment;

FIG. 10 is a left side elevational view of a multiple electrical outlet adapter showing a fourth embodiment of my new design, the right side elevational view being a mirror image, the top plan, front elevational and back elevational views thereof being the same as the first embodiment, and the bottom plan view thereof being the same as FIG. 4;

FIG. 11 is a left side elevational view of a multiple electrical outlet adapter showing a fifth embodiment of my new design, the right side elevational view being a mirror image, the top plan, front elevational and back elevational views thereof being the same as the first embodiment, and the bottom plan view thereof being the same as FIG. 4;

FIG. 12 is a front elevational view of a multiple electrical outlet adapter showing a sixth embodiment of my new design;

FIG. 13 is a left side elevational view thereof, the right side elevational view being a mirror image.

FIG. 14 is a top plan view thereof;

FIG. 15 is a bottom plan view thereof; the broken lines being included only for the purpose of illustrating the orientation of the receptacle per se and form no part of the claimed design;

FIG. 16 is a back elevational view thereof;

FIG. 17 is a left side elevational view of a multiple electrical outlet adapter showing a seventh embodiment

of my new design, the right side elevational view being a mirror image, and the top and bottom plan views and front and back elevational views thereof being the same as the sixth embodiment;

FIG. 18 is a left side elevational view of a multiple electrical outlet adapter showing an eighth embodiment of my new design, the right side elevational view being a mirror image, and the top and bottom plan views and front and back elevational views thereof being the same as the sixth embodiment;

FIG. 19 is a left side elevational view of a multiple

electrical outlet adapter showing a ninth embodiment of my new design, the right side elevational view being a mirror image, and the top and bottom plan views and front and back elevational views thereof being the same as the sixth embodiment; and,

FIG. 20 is a left side elevational view of a multiple electrical outlet adapter showing a tenth embodiment of my new design, the right side elevational view being a mirror image, and the top and bottom plan views and front and back elevational views thereof being the same as the sixth embodiment.
